ANGLE IRON BRACE

Ernest Soffer, Bronx, N. Y.

Application July 29, 1944, Serial No. 547,261

6 Claims. (Cl. 20—92)

This invention relates to new and useful improvements in angle iron braces.

More specifically, the invention proposes a new and improved angle iron brace which is particularly adapted to repair all kinds of wood work and which may also be used in new constructions.

The improved angle iron brace is characterized by an iron strip bent into a right angle and having a plurality of pointed prongs on the end portions of the arms of said right angle directed outwards of the right angle so that the brace may be used to reinforce internal corners of wood work such as chairs, tables and other articles. With the new construction it is possible to mount the brace in position within an interior angle without the use of screws or other fastening elements. It need only be hammered into position. The device will save time and is comparatively easy to handle.

It is possible to provide the iron strip with rib portions stamped from the material thereof for stiffening and reinforcing the arms of the brace. In accordance with the present invention it is proposed to cut from the material of the arms of the brace an auxiliary brace or portion having one of its ends integral with one of the arms of the brace and having its other end associated with elements by which it may be adjustably connected with the other arms of the brace. This auxiliary arm may be set after the angle iron brace is in position for more securely bracing the article upon which the brace is used.

Another object of the invention is the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an angle iron brace constructed in accordance with this invention.

Fig. 2 is a perspective view of the blank used for forming the brace shown in Fig. 1.

Fig. 3 is a perspective view of a brace constructed with reinforcing means.

Fig. 4 is an enlarged vertical sectional view taken on the line 4—4 of Fig. 3.

Fig. 5 is another perspective view of a brace constructed in accordance with the invention.

Fig. 6 is a fragmentary enlarged sectional view taken on the line 6—6 of Fig. 5.

Fig. 7 is a perspective view of the outer end of the auxiliary brace portion shown in Fig. 5.

Fig. 8 is an elevational view of Fig. 6 illustrated with the auxiliary brace portion removed.

Fig. 9 is a perspective view of an angle iron brace constructed in accordance with another form for use for a table.

Fig. 10 is a horizontal sectional view of an article with the new and improved angle iron brace shown in Fig. 9 applied.

The angle brace includes an iron or other metallic strip 10 bent into a right angle, as illustrated in Fig. 1, and having a plurality of pointed prong portions 11 on the ends of the arms 12 and 13 thereof. These prong portions 11 are directed outwards of the right angle. The angle brace is formed from a blank such as illustrated in Fig.

20 2. This blank is in the nature of a strip having prong portion 11 along the sides and the end of the end portions thereof. The strip 10 is bent at the center along the line AA. The prongs 11 are bent outwards.

25 25. The angle iron brace in accordance with this invention provides a simplified way of reinforcing furniture of all types, at the inner or concealed side of the furniture, without any screws or rivets.

30 30. In Figs. 3 and 4 a form is disclosed according to which rib portions 15 are formed along the arms 12 and 13 for stiffening and reinforcing said arms. These rib portions 15 are stamped from the material of the strip 10. They are embossed inwards of the right angle so that they do not interfere with the engagement of the arms against the faces of a right angle to be reinforced by the brace.

35 40. In Figs. 5—8 inclusive the form in accordance with the invention is shown. An auxiliary brace portion 18 is cut from the material of the arms 12 and 13 and has one of its ends, namely, the end 19, formed integral with one of the arms. The other end of the auxiliary brace portion 18 is formed with a T-shaped head 20. This head is cooperative with an embossed portion 21 embossed on one of the arms of the strip 10, and formed with a slot 22. The embossed portion 21 is of elongated shape. The slot 22 is extended longitudinally of the strip 10. At the center the slot 22 is formed with a transverse enlarged portion 23 through which said head 20 may pass.

45 50. The parts are so proportioned that the transverse end of the T formation of said head 20 may

pass through the slot portion 23; while the stem may slip along the slot 22.

A plurality of transverse recesses 24 are formed along the material of the embossed portion 21 to the sides of the slot 22. The shoulders 25 of the head end of the auxiliary brace portion 18 is engageable with these recesses 24 for rigidly holding the brace 18 in position.

The angle brace is mounted within a right angle portion of an article to be braced, by hammering the prongs 11 into the material to be braced. After the brace is in proper position the auxiliary brace 18 is forced into an auxiliary bracing position, preferably by hammering so that the shoulders 25 engage a suitable pair of the recesses 24 for holding the auxiliary brace 18 in correct bracing position. The correct position is one in which the brace 18 tends to securely and firmly hold the arms of the angle brace against the faces of the material being braced.

As shown in Figs. 9 and 10 the arms 12' and 13' are connected with each other with an inwardly set right angularly shaped portion 28. The arms 12' and 13' are also provided with additional prongs 11.

In Fig. 10 a horizontal sectional view of an article is shown comprising a corner square piece 30 and pieces 31 and 32 connected with the square piece 30 and projecting at right angles to each other. The angle iron brace shown in Fig. 9 is applied to these parts. Note particularly that the inwardly set right angularly shaped portion 28 engages the inner corner of the square piece 30. The angle iron brace serves to reinforce the pieces 30, 31 and 32 as a unit. It is pointed out that these pieces may comprise the leg and side arms of a kitchen table, this view being taken as though taken beneath the top of the table.

The auxiliary brace portion 18 as shown in Fig. 5 can similarly be applied to the form shown in Fig. 10.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An angle brace, comprising a metal strip bent into a right angle and having a plurality of pointed prongs on the end portions of the arms of said right angle directed outwards of said right angle, and an auxiliary brace portion cut from the material of said arms and having one of its ends integral with one of said arms, and means for adjustably connecting the other end of said brace portion with the other one of said arms.

2. An angle brace, comprising a metal strip bent into a right angle and having a plurality of pointed prongs on the end portions of the arms of said right angle directed outwards of said right angle, and an auxiliary brace portion cut from the material of said arms and having one of its ends integral with one of said arms, and means for adjustably connecting the other end of said brace portion with the other one of said arms, and a slot formed in the other one of said arms, and a central enlarged section through which the outer end of said

angle, and an auxiliary brace portion cut from the material of said arms and having one of its ends integral with one of said arms, and means for adjustably connecting the other end of said brace portion with the other one of said arms, the other end of said auxiliary brace portion having a T-shaped head portion engaging a slot formed in said other one of said arms.

3. An angle brace, comprising a metal strip bent into a right angle and having a plurality of pointed prongs on the end portions of the arms of said right angle directed outwards of said right angle, and an auxiliary brace portion cut from the material of said arms and having one of its ends integral with one of said arms, and means for adjustably connecting the other end of said brace portion with the other one of said arms, the other end of said auxiliary brace portion having a T-shaped head portion engaging a slot formed in said other one of said arms, said other one of said arms having an embossed portion in which said slot is formed.

4. An angle brace, comprising a metal strip bent into a right angle and having a plurality of pointed prongs on the end portions of the arms of said right angle directed outwards of said right angle, and an auxiliary brace portion cut from the material of said arms and having one of its ends integral with one of said arms, and means for adjustably connecting the other end of said brace portion with the other one of said arms, the other end of said auxiliary brace portion having a T-shaped head portion engaging a slot formed in said other one of said arms, said other one of said arms having an embossed portion in which said slot is formed.

5. An angle brace, comprising a metal strip bent into a right angle and having a plurality of pointed prongs on the end portions of the arms of said right angle directed outwards of said right angle, and an auxiliary brace portion cut from the material of said arms and having one of its ends integral with one of said arms, and means for adjustably connecting the other end of said brace portion with the other one of said arms, the other end of said auxiliary brace portion having a T-shaped head portion engaging a slot formed in said other one of said arms, said other one of said arms having an embossed portion in which said slot is formed, and said slot having a central enlarged section through which the outer end of said T-head may pass.

6. An angle iron brace comprising a metal strip bent into a right angle having two arms and an auxiliary brace portion cut from the material of said arms and having one of its ends integral with one of said arms, and means for adjustably connecting the other end of said brace portion with the other end of said arms.

ERNEST SOFFER.
